UNITED STATES PATENT OFFICE.

GEORGE M. HUBBARD, OF NEW HAVEN, CONNECTICUT, ASSIGNOR TO THE
W. & E. T. FITCH COMPANY, OF SAME PLACE.

DESIGN FOR A SNAP-HOOK.

SPECIFICATION forming part of Design No. 26,279, dated November 17, 1896.

Application filed October 5, 1896. Serial No. 607,965. Term of patent 14 years.

To all whom it may concern:

Be it known that I, GEORGE M. HUBBARD, of New Haven, in the county of New Haven and State of Connecticut, have invented a new 5 Design for Snap-Hooks; and I do hereby declare the following, when taken in connection with the accompanying drawings and the letters of reference marked thereon, to be a full, clear, and exact description of the same, and 10 which said drawings constitute part of this specification, and represent, in—

Figure 1, a plan view of a snap-hook embodying my design; Fig. 2 a side view of the same.

15 This invention relates to a design for snap-hooks; and it consists in the configuration and ornamentation, as herein described, and shown in the accompanying illustration.

As herein shown, the design consists of a

hook A, shank B, and eye C, each side of the 20 shank being ornamented by a raised tapered rib D, projecting forward from the junction of the eye C with the shank and appearing to be a continuation of the eye, and so that the eye is represented as if formed with forwardly-projecting ribs which overlap the 25 sides of the shank, all as shown in the accompanying illustration.

I claim—

The design for snap-hooks as herein shown 30 and described.

In testimony whereof I have signed this specification in the presence of two subscribing witnesses.

GEORGE M. HUBBARD.

Witnesses:

JOHN B. FITCH,

LUCIUS H. PRINDLE.
